UNITED STATES PATENT OFFICE

2,084,330

SEAMLESS PIPE OR TUBE MILL

Stevenson Findlater, McKeesport, Pa., assignor
to National Tube Company, a corporation of
New Jersey

Application November 21, 1934, Serial No. 754,168

4 Claims. (Cl. 80—13)

This invention relates to improvements in seamless pipe or tube mills, and more particularly to the compensation for changes in the size of the pass due to the expansive influence 5 of the highly heated work-piece.

In the manufacture of seamless pipes and tubes, considerable difficulty has been experienced in maintaining constant the distance between the various roll faces and the surfaces of the 10 mandrel plug, due to the expansion of the rolls, mandrel plug and of the mandrel bar supporting the plug. That is to say, as the rolls and mandrel plug acquire heat from the work-pieces being processed they will expand and their respective surfaces will be closer together. Similarly, as the mandrel bar acquires heat it will 15 increase in length and move the mandrel plug further into the metal pass and, accordingly, closer to the surfaces of the rolls. This decreased 20 distance between the various metal working surfaces causes the wall thickness of the work-piece being processed to vary, due to a more substantial reduction in the wall of the work-piece when the rolls and mandrel bar are hot than would be the 25 case were they cold.

The temperature of a seamless pipe or tube mill is usually no higher at the end of a long period of operation than it was at the beginning. This is for the reason that the mill is started 30 without cooling water on the rolls and heated billets passed therethrough until the rolls acquire a desired temperature. At this time the rolls are sprayed with water in order that the temperature will not rise greatly beyond that 35 desired. In this manner the general temperature of the mill is maintained as desired, but as each highly heated billet, or work-piece, moves through it, the temperature of its elements is temporarily raised. This temporary rise in temperature causes a correspondingly temporary expansion, particularly of the mandrel bar; the effects of which the present invention seeks to 40 avoid.

In addition, it is often desirable to regulate 45 the relative positions of various metal working rolls, even when cold, in accordance with the temperature of the work-piece, and thus modify the pressure thereof in order to obviate variances in the product. In a copending application entitled "Apparatus for making tapered work-pieces" filed December 29, 1934 and bearing Serial Number 759,803, I have disclosed apparatus 50 which is in many respects similar to that disclosed herein. This copending application is, however, concerned with making a tubular work-

piece which is tapered in both outside diameter and wall thickness; and the apparatus thereof is therefore constructed and arranged to accomplish this result by enlarging the pass.

One object of the invention is to provide novel 5 means for automatically compensating to exactness for the expansion of metal working rolls and maintain constant the distance between the surfaces of the various rolls.

Another object is the provision of novel automatically actuated mechanism for withdrawing either and/or a work roll or rolls or an idle roll or rolls in exact ratio to the expansion thereof.

A further object of the invention is to provide a novel mechanism for automatically withdrawing a roll or rolls in exact ratio to the expansion of the mandrel bar and/or the metal working rolls of a seamless tube mill, resulting in a constantly maintained distance between all of the various metal working surfaces.

A still further object is to provide automatic and powerful means, operating under a heavy thrust, for moving at least one roll from the roll pass slowly and in exact ratio with the expansion of metal working rolls and/or the expansion of a mandrel bar, together with automatically actuated means for stopping the operation of said first named means and rapidly returning the roll or rolls to their original relative positions.

A still further object is to provide a novel construction of the class described which can be installed on existing mills with but little modification and expense.

These and further objects of the invention 35 will appear after referring to the drawings, in which:

Figure 1 is a plan showing the apparatus of the invention applied to a seamless tube mill with the work-piece in section.

Figure 2 is a view taken on the line II—II of Figure 1, and showing part of the apparatus in section.

Figure 3 is an end view taken on the line III—III of Figure 1.

Figures 4 and 5 are electrical circuits for operating the various elements of the invention.

Referring more particularly to the drawings, the numeral 2 designates a pair of metal working rolls which are shown as being of the "disk" 50 type, but might well be of any of the well known constructions. Ordinarily, in seamless tube practice both of the rolls 2 will be power actuated, but it is to be understood that one of the same may be idle, and it is even within the contem- 55

plation of the invention to apply the principles thereof to any metal working mill employing a plurality or multiplicity of rolls which may be, according to the invention, modified as to their relative positions, either in combination or otherwise.

Each of the rolls 2 is mounted on a shaft 3 and driven through suitable mechanism, such as a gear B and pinion B', the latter having an elongated surface to permit relative longitudinal movement of the gear B and shaft 3 on which it is mounted.

A mandrel bar 4 is disposed in the longitudinal direction of feed of a work-piece, or tube A, and provided on one of its ends with a mandrel plug 4^a which is adapted to internally support the work-piece while it is being processed by the rolls 2.

A suitable coupling 3^a is provided for connecting one of the roll shafts 3 to a screw 5 in such manner as to permit independent rotation of the roll shaft. The screw 5 is disposed in a nut 6 which is journaled for rotation in suitable bearings 7. A worm wheel 8 is keyed to the nut 6 for rotation therewith, and is in mesh with a worm 9, which is mounted on a shaft 10 of a large gear 11.

A motor 12 is positioned somewhat adjacent the large gear 11 and has a pinion 13 associated therewith for rotating a gear 14 which is mounted on a shaft 15. The shaft 15 carries one member of a magnetic clutch, generally indicated at 16, while a cooperating shaft 15^a carries the cooperating clutch member. A pinion 17 is mounted on the shaft 15^a and in mesh with a gear 18, which is mounted on one end of a shaft 19. The shaft 19 is provided at its other end with a pinion 20 which is in constant mesh with the large gear 11.

40 A second motor 22 is positioned somewhat closer to the large gear 11 and is provided with a pinion 23 which is in constant mesh therewith. A suitable magnetic brake, generally indicated at 24, is provided for the motor 22.

45 The rotation of the motor 12 is automatically compensated for differences in resistance to metal displacement caused by introducing metal of varying temperatures into the rolls. The operation is such that the variation in temperature of the work-piece being processed, as measured by photoelectric, optical radiation, or other pyrometer, will be transmitted to the compensator motor 12, in such manner as to increase or retard the rotation thereof, thereby varying the rate at which the compensator operates.

50 Any suitable and conventional electric wiring circuits, including the pyrometer device, relays, and preferably also push-buttons, are provided for the motors 12 and 22, the magnetic clutch device 16, and the magnetic brake 24 for the motor 22.

55 In operation, a tube A, which is shown as having been previously pierced, is introduced between the rolls 2 while supported internally by the mandrel plug 4^a. The tube continues through the mill until a suitable load relay, or push-button, is operated to energize the magnetic clutch 16 and release the magnetic brake 24, the rate of rotation of the shaft of the motor 12 being controlled through the suitable resistance mentioned. The rotation of this shaft permits the motor pinion 13, driving through the mechanism, or gear train 14, 17, 18, 20, 11, 9 and 8 to rotate the nut 6 and withdraw the screw 5, thereby correcting or

maintaining the distance between the rolls 2 and the surfaces of the mandrel plug 4^a.

5 After the motor 12 has been actuated to cause the screw 5 to be retracted sufficiently by the nut 6, the return movement of the roll must be quickly effected pending the arrival of the next tube. As the pinion 23 on the shaft of the motor 22 is in constant mesh with the large gear 11, a suitable relay, or the operator attending the device, momentarily energizes the magnetic brake 24 for the motor 22. This operation at the same time instantaneously deenergizes the magnetic clutch 16 and disengages the motor 12. The motor 22 is then actuated to reverse the motion of the gear 11 to rapidly return the roll to a position predetermined by suitable limit switches which automatically stop the motor 22 and at the same time applies the brake 24.

When the motor 22 is energized, the large gear 11, which is in constant mesh with the pinion 23, causes the latter, gear 18 and pinion 17 to rotate, since the pinion 20 and gear 18 are mounted rigidly on the common shaft 19. The motion through this gear train ends here, however, because the magnetic clutch 16 is not energized, permitting the shaft of the motor 12, pinion 13, gear 14 and shaft 15 to remain at a standstill when the motion transmitted by the motor 22 returns the roll to the position required for the entry of the next tube.

30 Referring to Figures 4 and 5 of the drawings, I have disclosed, in a diagram, one form of electrical control which will function to operate the elements of the invention in the manner previously described. In this diagram the numerals 30 and 31 designate suitable power lines carrying a normal voltage; such as 220 V.

35 A master switch 33 is provided for operating the motor 12, which serves to retract one of the metal working rolls 2, and is connected between the power lines 30 and 31 by a line 34. The master switch 33 is provided with an operating lever 35 and the usual contacts 36, 37, 38, 39, 40 and 41. A low-voltage coil 43 is connected in the line 34 for the master switch 33, and has two pairs of contacts 43^a and 43^b which it serves to actuate.

40 The contact 36 of the master switch 33 is connected to the line 34, between the low-voltage coil 43 and its contacts 43^a, by a line 45. A line 46 connects the contact 37 of the master switch 33 to the line 34 through the contacts 43^b of the low-voltage coil 43 and has included therein a pair of coils 47.

45 A line 48 is connected to the contact 38 of the master switch 33 and has included therein an auxiliary switch 53^a, while a line 49 is connected to the contact 39 and has included therein an auxiliary switch 47^a. The lines 48 and 49 are connected to the line 34 through the contacts 43^b of the low-voltage coil 43 by a line 50 which has included therein a coil 51.

50 The contact 40 of the master switch 33 is connected to the line 34 through the contacts 43^b of the low-voltage coil 43 by a line 52 in which there is included a pair of coils 53.

55 A line 54 is provided for connecting the contact 41 of the master switch 33 through the contacts 43^b of the low-voltage coil 43, and includes a series of coils 55, 56 and 57, together with an auxiliary switch 51^b. The auxiliary switches 47^a and 53^a are operated by the coils 47 and 53, respectively.

60 The motor 12 is connected to the power lines 30 and 31 by a line 56 and includes in its circuit contacts 47^b and 47^c and 53^b and 53^c, which are 65

operated by the coils 47 and 53, respectively. A series of contacts 55^a, 56^a and 57^a, are also included in the line 56, together with a pair of contacts 51^a. The contacts 55^a, 56^a and 57^a are operated by the series of coils 55, 56 and 57, respectively. The auxiliary switch 51^b and the contacts 51^a are both operated by the coil 51.

The photoelectric pyrometer device X is connected by a line 59 with a series of relays 60, 61, 62, 63, 64 and 65, which in turn operate a field rheostat 66. Each of these relays is adjusted to trip at a definite temperature. This field rheostat is connected in a line 67 between the power lines 30 and 31, with the shunt field for the motor 12, which is designated at 12^a, and a hand operated rheostat 68.

Referring to Figure 5 of the drawings, it is to be noted that the motor for rotating the metal working rolls 2 is indicated at 70, being connected by a line 71 with suitable power lines 72 and 73. While one motor 70 is illustrated in the drawings and may be used to drive both metal working rolls 2 through the medium of suitable gearing (not shown), the invention also contemplates the driving of each roll with an individual motor. The power lines 72 and 73 furnish the motor 70 with current of a considerably higher voltage than that furnished through the power lines 30 and 31; as for instance 600 volts. A shunt 74 is included in the line 71 between the power line 72 and the motor 70. A line 75 connects the shunt 74 with one end of a load relay 76. Another line 77 connects the shunt 74 with the other end of the load relay 76 and has included therein a limit switch 78.

The magnetic clutch 16 which is carried on the shafts 15 and 15^a is connected between the power lines 30 and 31 by a line 80, which has included therein two pairs of contacts, as at 76^a and 76^b. The magnetic brake 24 for the motor 22 is connected by a line 81 with the power lines 30 and 31, and includes in circuit on each side thereof a pair of contacts, as at 109^a and 109^b, respectively.

A line 83 is connected to the line 80 between the power line 30 and the contacts 76^a and to the line 81 between the contacts 109^a and the magnetic brake 24, and includes a pair of contacts 76^c. A similar line 84 is connected to the line 80 between the power line 31 and the contacts 76^b and to the line 81 between the contacts 109^b and the magnetic brake 24 and includes a pair of contacts 76^d.

The contacts 76^a, 76^b, 76^c and 76^d are all operated by the load relay 76.

A master switch 86 is provided for operating the motor 22 which returns the movable metal working roll 2 to its original position in the mill. This master switch 86 is connected between the power lines 30 and 31 by a line 87, and provided with an operating lever 88 and contacts 89, 90, 91, 92, 93 and 94. A low-voltage coil 96 is connected in the line 87 for the master switch 86 and has two pairs of contacts 96^a and 96^b which it serves to operate.

The contact 89 of the master switch 86 is connected to the line 87 between the low voltage coil 96 and its contacts 96^a by a line 97.

A line 98 connects the contact 90 of the master switch 86 to the line 87 through the contacts 96^b of the low-voltage coil 96 and includes therein a limit switch 100 and a pair of coils 101.

A line 102 is connected to the contact 91 of the master switch 86 and includes a limit switch 103 and an auxiliary switch 113^a, while a line

105 is connected to the contact 92 of the master switch 86 and has included therein a limit switch 106 and an auxiliary switch 101^a. The lines 102 and 105 are connected to the line 87 through the contacts 96^b of the low-voltage coil 96 by a line 108 which has included therein a pair of coils 109.

The contact 93 of the master switch 86 is connected to the line 87 through the contacts 96^b of the low-voltage coil 96 by a line 110 which has included therein a limit switch 112 and a pair of coils 113.

The limit switches 100 and 103 are suitably arranged to open when the motor 22 has placed the metal working roll 2 in its original position in the mill, while the limit switches 106 and 112 are arranged to open when the roll is in its extreme remote position with respect thereto.

A line 114 connects the contact 94 of the master switch 86 to the line 87 through the contacts 96^b of the low-voltage coil 96 and includes a series of coils 115, 116 and 117, and an auxiliary switch 109^d.

It is to be noted that an auxiliary switch 76^e is interposed between the contacts 96^b of the low-voltage coil 96, and the coils 101, 109 and 113 in the lines 98, 108 and 110, respectively. The auxiliary switches 101^a and 113^a are operated by the coils 101 and 113, respectively.

The motor 22 is connected to the power lines 30 and 31 by a line 122 and includes in its circuit contacts 101^b and 101^c and 113^b and 113^c, which are also operated by the coils 101 and 113, respectively. The series field for the motor 22 is included in this line 122, being designated at 22^a, and also a series of contacts 115^a, 116^a and 117^a, which are operated by the coils 115, 116 and 117, respectively. A pair of contacts 109^c are also included in a line 122 between the series of contacts 115^a, 116^a, and 117^a and the power line 31.

The contacts 109^a, 109^b, 109^c and the auxiliary switch 109^d are all operated by the coils 109.

In operation: The operator of the mill moves the lever 35 of the master switch 33 to the "out" position. At the time the lever 35 was resting in the "off" position, the low-voltage coil 43 was closed, and is maintained by one of its contacts 43^a. The movement of the lever 35 closes the contacts 39, 40 and 41 of the master switch, thus energizing the coil 53 to close the contacts of the auxiliary switch 53^a and the contacts 53^b and 53^c; and the coil 51 to close the contacts 51^a, and the contacts of the auxiliary switch 51^b. The closing of the contacts of the auxiliary switch 51^b energizes the coils 55, 56 and 57, thus closing the contacts 55^a, 56^a and 57^a. Upon the closing of the contacts 55^a, 56^a and 57^a the motor 12 will rotate at a speed predetermined by the setting of the hand operated rheostat 68.

At the time of moving the lever 35 of the master switch 33 to the "out" position, the operator also moves the lever 88 of the master switch 86 to the "in" position. No operation results from this last named movement due to the fact that the metal working rolls 2 are in position to receive the work-piece A and the limit switches 100 and 103 are open.

As the work-piece A moves between the metal working rolls 2 and over the mandrel plug 4^a, the power required by the motor 70 passes through the shunt 74. The "voltage drop" across the shunt energizes the load relay 76 which closes the contacts 76^a, 76^b, 76^c and 76^d and opens the auxiliary switch 76^e. The closing of the contacts 76^a, 76^b, 76^c and 76^d energizes the magnetic clutch 16 and the magnetic brake 24. In this

manner the motor 12 is caused to rotate the nut 6 to withdraw one of the metal working rolls 2. The speed with which the motor 12 initially operates is, of course, determined by the setting of the hand operated rheostat 68, as previously mentioned.

The photoelectric pyrometer device X is set for a predetermined temperature indication and if the temperature of the work-piece A, as it passes the point upon which it is "trained" is either above or below this indication, the relays 60 to 65, inclusive, are caused to function. The functioning of the relays 60 to 65, inclusive, will include or delete sections of the field rheostat 66, to increase or decrease the speed of operation of the motor 12, which is withdrawing one of the metal working rolls 2. It will thus be seen that this rate of withdrawal is in direct proportion to the temperature of the work-piece A.

20 The power required by the motor, or motors, 10, which drives the metal working rolls 2, will approach zero after the trailing end of the work-piece A has emerged from the mill. This causes the "voltage drop" across the shunt 74 to approach zero, and the consequent deenergization of the load relay 76. The deenergization of the load relay 76 causes the opening of the contacts 76^a, 76^b, 76^c and 76^d, to deenergize the magnetic clutch 16 and the magnetic brake 24. The motor 12 is thus caused to cease the withdrawal of the metal working roll 2.

The opening of the contacts 76^a, 76^b, 76^c and 76^d causes the auxiliary switch 76e to close. The closing of this auxiliary switch energizes the coils 109 and the coils 101 through the contacts 91 and 90 of the master switch 86. The energization of the coils 109 closes the contacts 109^a, 109^b and 109^c and the contacts of the auxiliary switch 109d. The energization of the coils 101 closes the contacts of the auxiliary switch 101^a and the contacts 101^b and 101^c. The closing of the contacts 109^a and 109^b releases the magnetic brake 24, and the closing of the contacts of the auxiliary switch 101^a and the contacts 101^b and 101^c start the motor 22.

The closing of the contacts of the auxiliary switch 109d energizes the coils 115, 116 and 117 to close the contacts 115^a, 116^a and 117^a. This brings the motor 22 up to full speed.

50 The limit switches 103 and 100 open when the motor 22 has restored the metal working roll 2 to its original position, the former deenergizing the coils 109 which causes the opening of the contacts 109^a, 109^b, 109^c and the contacts of the auxiliary switch 109d. The opening of the limit switch 100 deenergizes the coils 101 which causes the opening of the contacts of the auxiliary switch 101^a, and the contacts 101^b and 101^c. The opening of the various contacts effected by the opening of the limit switches 103 and 100 causes the deenergization of the motor 22 and the magnetic brake 24, thereby setting the latter.

The entire equipment is thus set for another 65 cycle of operation, which is again initiated by

the operation of the mill in the manner previously described.

While I have shown and described certain specific embodiments of my invention, it will be understood that I do not wish to be limited thereto, since various modifications may be made without departing from the scope of my invention, as defined by the following claims.

I claim:

1. A metal working roll adjusting mechanism 10 comprising a screw associated with said roll, a nut on said screw, a worm gear on said nut, a worm for said worm gear, a gear for rotating said worm, a pinion for said last named gear, a motor and reduced gearing associated with said pinion for rotating said screw to move said roll away from a work-piece being processed thereby, a second motor for rapidly returning said roll to its initial position, and a driving connection between said last named motor and the gear for rotating said worm.

2. A seamless pipe or tube mill comprising, in combination, at least one power actuated metal working roll, a roll for coacting with said first named roll, a mandrel bar, a mandrel plug supported by said mandrel bar, said mandrel plug being disposed intermediate said rolls, means for slowly withdrawing at least one of said rolls to compensate for expansion and maintain substantially constant the distance between said rolls and the surfaces of said mandrel plug while a pipe or tube is being acted upon thereby, a means responsive to the temperature of said pipe or tube for controlling the operation of said last named means, and means for returning said second named roll to its initial position.

3. A seamless pipe or tube mill comprising, in combination, at least one power actuated metal working roll, a roll for coacting with said first named roll, a mandrel bar, a mandrel plug disposed intermediate 40 said rolls, means for withdrawing at least one of said rolls to maintain a desired relationship between said rolls and the surfaces of said mandrel plug while a pipe or tube is being acted upon thereby, means responsive to the temperature of said pipe or tube for controlling the speed of operation of said withdrawing means, and means for returning the withdrawn roll to its initial position.

4. A seamless pipe or tube mill comprising, in combination, at least one power actuated metal working roll, a roll for coacting with said first named roll, a mandrel bar, a mandrel plug supported by said mandrel bar, said mandrel plug being disposed intermediate said first and second named rolls, means for withdrawing at least one of said elements to maintain a desired relationship between said rolls and the surfaces of said mandrel plug while a pipe or tube is being acted upon thereby, a speed-adjuster for said means, means responsive to the temperature of said pipe or tube for controlling said speed-adjuster, and means for returning the withdrawn element to its initial position.

STEVENSON FINDLATER. 65
